UNITED STATES PATENT OFFICE.

ROBERT C. STEVENS, OF ERIE, PENNSYLVANIA, ASSIGNOR TO SKINNER ENGINE COMPANY, OF ERIE, PENNSYLVANIA, A CORPORATION OF PENNSYLVANIA.

STEAM-ENGINE.

1,132,226.

Specification of Letters Patent. Patented Mar. 16, 1915.

Application filed September 28, 1913. Serial No. 791,993.

To all whom it may concern:

Be it known that I, ROBERT C. STEVENS, a citizen of the United States, residing at Erie, in the county of Erie and State of Pennsylvania, have invented certain new and useful Improvements in Steam-Engines; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

15 My invention relates to steam engines and particularly to that type of steam engine in which steam is permitted to exhaust from the cylinder at a point removed longitudinally from the intake ports, whereby the 20 partially cooled steam, during the exhaust period, is not forced against the hotter portions of the cylinder. This type is commonly called the "uniflow" type. Engines of this uniflow type are adapted for use in 25 combination with a steam condenser wherein a partial vacuum in the exhaust is maintained, which is communicated to the engine cylinder upon the opening of the exhaust ports by the piston, and upon the return stroke of the piston, after the closing 30 of the exhaust ports thereby, the partial vacuum in the cylinder must be converted to pressure before the clearance, inseparably incident to engine construction, is properly 35 filled preparatory to the admission of steam thereinto. When, however, engines of this type are designed to be used without a condenser, auxiliary exhaust ports are located between the steam intake ports and the 40 exhaust ports, so that compression commences only after such auxiliary exhaust ports are closed. Heretofore it has been customary to provide engines of this type with a valve for opening and closing each intake port, 45 and each auxiliary exhaust port, thereby necessitating the employment of four valves, and their accompanying actuating gear. It is also customary, when high efficiency is required, to provide the cylinder heads and 50 end portions of the cylinder of uniflow engines with steam jackets, in order that the highly heated inflowing steam will not immediately condense on the internal surface of the cylinder, thereby impairing the efficiency of the steam after it enters the cyl-

inder. In such cases, one side of the steam jacket is exposed to the atmosphere and the heat radiations therefrom are lost, which loss shows itself in increased consumption of fuel.

It is the object of my invention, therefore, to so construct a steam engine of the uniflow type, as to overcome the difficulties and objections heretofore experienced in the construction and operation of uniflow engines, and I accomplish this by constructing the engine so as to have a central steam admission, with exhaust at the ends of the cylinder, which enables me to economically utilize heat from the steam flowing toward the inlet ports of the cylinder, to maintain those portions of the cylinder adjacent to the stem inlet ports, at the maximum degree of heat, without the aid of end jackets; also that all of the valve operated ports leading from the interior of such an engine cylinder, may be adapted to be opened and closed by a single valve, preferably of the steam-tight, semi-balanced type, although a plain, unbalanced, or ordinary balanced flat, or piston, valve may be used in accordance with my invention, if desired, although engines constructed in accordance with the central steam and end exhaust principle, as hereinafter described, may be adapted to the use of multiple valves, if desired.

Other features of my invention will appear hereinafter in the specification, and are illustrated in the accompanying drawings, in which:

Figure 1, is a longitudinal, horizontal section on the line X—X in Figs. 2 and 3. Fig. 2, is a transverse section on the line y—y in Fig. 1. Fig. 3, is a transverse section on the line z—z in Fig. 1.

In these drawings, A, indicates a steam engine cylinder provided with a central division wall A', having a chamber a, therein for the reception of live steam. There are also provided in the wall of the cylinder A, steam inlet ports a' a', located adjacent to each side of the division wall A'; and adjacent to each end of the cylinder A, there are provided main exhaust ports B and B', which communicate with circumferential exhaust chambers B², with which an exhaust pipe B³, communicates. I also provide, when required, a circumferential steam chamber a², around the central portion of the cylinder A, for the purpose of extending the

application of heat by means of live steam somewhat toward the exhaust ports B and B', of the cylinder A. In order to prevent excessive compression in the cylinder A, when used as a non-condensing engine, I provide auxiliary exhaust ports C C', which are located between the steam inlet ports a', and exhaust ports B, and B', at such points as may be found best adapted to secure the results desired. I have found that a desirable location at which to place these auxiliary exhaust ports, is at substantially two thirds of the distance between the main exhaust ports B and B', and the steam inlet ports a'; but others may find it desirable to vary this location.

The division wall A', is provided with an opening therethrough, which is provided with a stuffing-box mechanism D, through which a piston-rod E, passes and upon the piston-rod E, I secure pistons F, and F', one on each side of the central division wall A'. Upon the side of the cylinder A, I provide a valve-chest G, which communicates with the central steam chamber a, in the division wall A', and with the steam intake ports a', and auxiliary exhaust ports C, and C'. A passage g, is also provided from each end of the valve-chest G, to the exhaust chambers B², at each end of the cylinder A. The valve chamber G, is provided with a valve seat surface G', on the inner wall thereof; through which the auxiliary exhaust ports C, and C', the steam inlet ports a', and the central steam chamber a, enter thereinto, and is also provided with the usual valve-chest cover G². Upon the valve-seat surface G', I place a slide valve H, preferably of the semi-balanced, expanding type adapted to alternately close the steam inlet port a', and open the auxiliary exhaust port C, at the left hand end of the cylinder, and open the steam inlet port a', and close the auxiliary exhaust port C', at the right hand end of the cylinder, while not at any time closing the opening from the steam chamber a, in the division wall A', into the interior of said valve. The valve H, is provided with the usual valve-stem H², which operates through the usual stuffing-box mechanism g', and is connected with the eccentric mechanism (not shown) of the engine, in the usual manner.

The ends of the cylinder A, are closed by means of heads J and J', the head J', being provided with stuffing-box mechanism j, of usual and ordinary construction. These cylinder heads are of no importance to the successful operation of the engine when used as a non-condensing engine, but when the engine is used as a condensing engine, they serve to maintain the vacuum incident to the condensing of steam in an inclosed chamber.

From the ends of the cylinder A, adjacent

to each head there is a relief port K, which communicates with the exhaust, as shown in broken lines in Fig. 1, for the purpose of preventing any back pressure between the pistons F and F', and the cylinder heads J 70 and J', and to carry off any vapor which might escape around the pistons. It will be noticed that the sum of the circumferential area of the two pistons F and F', is substantially equal to the circumferential 75 area of the piston in the ordinary type of uniflow central exhaust engine.

The steam chamber a, in the division wall A', is provided with a radial web a³, (see Fig. 3) which causes steam admitted through the steam inlet opening a', to make a complete circuit of the chamber a, before entering the valve H, in the valve-chest G, thereby thoroughly and continuously heating the division wall A', and the portions 85 of the cylinder A, adjacent thereto, thereby preventing condensation within the cylinder upon those portions of its interior surface.

In the operation, steam is admitted into 90 the chamber a, through the opening a', and from thence into the valve H. In Fig. 1, the valve H, is shown as opening the steam inlet port a', to admit steam behind the piston F', to move the 95 pistons F and F', and piston-rod E, toward the right. During this movement of the piston the auxiliary exhaust port C', is closed by the valve and the auxiliary exhaust port C, is opened. Steam follows the 100 piston F', at approximately throttle pressure until the valve H, cuts it off in the usual manner, after which it expands and its pressure is reduced until it is released by the piston F', passing and uncovering the main 105 exhaust ports B', at the end of the stroke. Under certain conditions of proportion or adjustment, the valve H, may open the auxiliary exhaust C', slightly before the piston F', passes the main exhaust port B'; but the 110 exhaust action of the steam remains practically the same. During this stroke of the piston F', the steam is exhausted from the right hand side of the piston F, through the exhaust ports B and C, until the piston 115 F, has passed and covered the auxiliary exhaust port C, at which time the steam remaining in the space between the port C, and the head A', is imprisoned to give the well known advantage of compression. 120 Under certain conditions of proportion and adjustment, the valve H, may close the auxiliary exhaust port C, slightly before the piston F, covers said port, but this will not in any manner alter the advantageous operation of and the necessity for the auxiliary exhaust port C. Vacuum is prevented from forming on the left hand and right hand sides of the pistons F, and F', by reason 125 of the fact that this space is, at all times,

in communication with the exhaust by means of the ports K. It will be readily appreciated, however, that while the foregoing description refers particularly to a non-condensing engine, the mechanism is equally operative as a condensing. On the return stroke the above cycle of operations is repeated.

From the foregoing description, it will be obvious that my invention enables me to construct a steam engine having the advantages of a uniflow engine, equally adapted for condensing and non-condensing purposes, as the auxiliary ports C and C', relieve excessive compression when not operating as a condensing engine. It also enables me to construct a steam engine in which the live steam is introduced into a central chamber and the surfaces heated thereby are not exposed to the atmosphere, and consequently do not waste steam by radiation as is the case with central exhaust, end jacketed cylinders, and do not require the same amount of care in jacketing to utilize the maximum degree of heat in the engine. It also enables me to eliminate the complicated valve gear accompanying the use of multiple valves, as I can employ a single valve and obtain the beneficial results accomplished by the ordinary central exhaust uniflow engine with four valves.

Having thus fully described my invention so as to enable others to construct and utilize the same, what I claim as new and desire to

secure by Letters-Patent, is:—

1. In a steam engine the combination of a cylinder having a steam inlet port at one end and steam exhaust ports at the opposite end thereof, a piston in said cylinder adapted to control the exhaust from said cylinder, a valve mechanism communicating with said inlet port, a hollow head closing said cylinder at the steam intake end thereof having a steam inlet opening thereinto, and a steam passage therefrom to said valve mechanism, a radial division wall in said hollow head extending from the central portion to the periphery thereof between said inlet opening and the passage to said valve mechanism, and means to operate said valve mechanism, substantially as set forth.

2. In a steam engine, the combination of a pair of cylinders in tandem each having exhaust ports adjacent to their outer ends, and each having steam inlet ports at their inner ends, valve mechanism communicating with said inlet ports, a hollow division wall between said inlet ports having a steam inlet opening thereinto and a steam passage therefrom into said valve mechanism, a radial division wall in said hollow wall extending from the central portion to the periphery thereof between said inlet opening and said steam passage to said valve mechanism, con-

nected pistons in said cylinders adapted to control the exhaust from said cylinders, and means to operate said valve mechanism, substantially as set forth.

3. In a steam engine, the combination of a cylinder having steam inlet ports in its intermediate portion thereof, main exhaust ports adjacent to the ends thereof, and auxiliary exhaust ports in the wall thereof between said steam intake ports and the main exhaust ports, a division wall between said steam intake ports, a piston-rod therethrough, pistons secured on said piston-rod at each side of said division wall, a valve-chest with which said steam inlet ports and said main exhaust and auxiliary ports communicate, and a valve therein adapted to cover and uncover said steam inlet ports and said auxiliary exhaust ports, substantially as set forth.

4. In a steam engine, the combination of a cylinder having steam inlet ports in its intermediate portion thereof, main exhaust ports adjacent to the ends thereof, and auxiliary exhaust ports in the wall thereof between said steam intake ports and said main exhaust ports, a division wall between said intake ports having a steam chamber, a piston-rod therethrough, a piston secured thereon at each side of said division wall adapted to cover and uncover said main exhaust ports, and valve mechanism adapted to open and close said intake and auxiliary exhaust ports, substantially as set forth.

5. In a steam engine, the combination of a cylinder having steam inlet ports in the intermediate portion, main exhaust ports adjacent to each end thereof, and auxiliary exhaust ports in the walls of said cylinder between said steam inlet ports and main exhaust ports, a division wall between said steam inlet ports, a piston-rod extending through said division wall pistons secured on said piston rod and adapted to cover said main exhaust ports and said auxiliary exhaust ports during the interval of passing the same on its reciprocations, and valve mechanism adapted to alternately open said intake ports, and alternately open said auxiliary exhaust ports, substantially as set forth.

6. In a steam engine, the combination of a cylinder having steam inlet ports in its intermediate portion, main exhaust ports adjacent to each end thereof and auxiliary exhaust ports in the wall of said cylinder between said steam inlet ports and main exhaust ports, a division wall between said steam inlet ports, a piston-rod extending through said division wall, pistons secured on said rod at each side of said division wall so as to pass said main exhaust ports during their reciprocations, and valve mechanism at one side of said cylinder adapted to open

and close said steam intake ports and said auxiliary exhaust ports, substantially as set forth.

7. In a steam engine the combination of a pair of cylinders in tandem, each cylinder having a main exhaust port adjacent to the outer end thereof, an inlet port at the inner end thereof and an auxiliary exhaust port in the wall thereof between said inlet and main exhaust ports, connected pistons in the respective cylinders, and a single valve controlling said inlet and auxiliary exhaust ports, substantially as set forth.

8. In a steam engine, the combination of a pair of cylinders in tandem, with a live-steam space therebetween, each cylinder having a main exhaust adjacent to its outer end,

an inlet port at its inner end and an auxiliary exhaust port in the wall thereof, between said main exhaust and inlet ports, a steam-chest at one side of said cylinders communicating with said live-steam space, a slide valve adapted to receive steam from said live-steam space and control said inlet and auxiliary exhaust ports in both of said cylinders, and connected pistons in said cylinders controlling said main exhaust ports, substantially as set forth.

In testimony whereof I affix my signature, in presence of two witnesses.

ROBERT C. STEVENS.
